UNITED STATES PATENT OFFICE.

PATRICK KENNEDY, OF NEW YORK, N. Y.

ELECTRIC SIGNALING DEVICE.

No. 824,988.

Specification of Letters Patent.

Patented July 3, 1906.

Application filed October 13, 1904. Renewed December 15, 1905. Serial No. 291,851.

To all whom it may concern:

Be it known that I, PATRICK KENNEDY, a citizen of the United States, residing in the borough of Brooklyn, in the county of Kings, in the city and State of New York, have invented certain new and useful Improvements in Electric Signaling Devices, of which the following is a specification.

This invention relates to the general class of automatic signaling devices or instruments employing electricity as a means of transmission, of which fire-alarm signal-transmitters are types, and it is herein illustrated as embodied in a fire-alarm signaling device of the non-interfering kind or type. It may be briefly stated here that in the installation of a system of non-interfering fire-alarm signal transmitters or boxes these latter are placed in the same electric circuit and so arranged that an alarm-signal may be sent from any signal-box to a central station, and in order that they may not interfere should an attempt be made to send a plurality of signals at the same time the operation of sending a signal from one box will disable all the others from sending a signal for the time being. In all of these systems, so far as I am aware, the operator or person wishing to send the signal must himself set the mechanism in motion, and if his box is disabled by some other box already in operation his efforts will be to no purpose. If he wishes to send a signal, he must wait until the line is clear and then repeat the operation.

According to the present invention, which is herein shown as operating on a closed circuit, the person purposing to send a signal merely presses a button or performs some equivalent operation which opens a circuit. The button when pressed in is locked or held by a detent in the position set by the pressure and the operator may go away, leaving the mechanism to take care of the sending of the signal. If there is no other signal being sent by any other transmitting instrument in the system, the instrument so set by the pressure on the button will send in its signal in due time. On the other hand, if any number of signals are being already sent in from other instruments in the system the box set as above will in its turn automatically send in its signal. To illustrate this, let it be supposed that there are ten signal-transmitting instruments in the system, and these are so adjusted, as will be hereinafter explained, that they may be numbered from "1" to

"10" and that the buttons of all of these ten instruments are pressed at the same instant. In this case No. 1 will first send in its signal, then No. 2, then No. 3, and so on to No. 10, and this will be effected automatically and without any after manipulation by the senders. The signals may from first to last be sent, say, some minutes apart; but they will all be sent in proper order.

To provide an instrument which will accomplish the above result is the object of the present invention, and one embodiment of the invention is illustrated in the accompanying drawings, wherein—

Figure 1 is a somewhat diagrammatic view showing the mechanism of the transmitter substantially in front elevation in its box. Fig. 2 is a plan of the mechanism, the box being in horizontal section. Fig. 3 is a side view of the mechanism as seen from the left in Figs. 1 and 2, the box being in section. Fig. 4 is a diagrammatic view showing how a plurality of the transmitters are connected in circuit. Fig. 5 is an illustrative detail view of the splined stem of the push-button and attached parts.

Before proceeding to describe the particular features of the instrument in which the present invention resides, it may be explained that this instrument in the form herein illustrated employs a number of instrumentalities which are common in this class of devices—namely, a break-contact wheel, clock mechanism for driving said wheel, a detent device which holds said driving mechanism from operating, an electromagnet for releasing the mechanism, and perhaps other minor features; but the invention is not limited to any special means for winding the operative mechanism nor indeed to any special kind of such mechanism.

As herein shown, the instrument is in a closed circuit, and the results are produced by breaks in this circuit.

In the principal views, A designates an inclosing box, of which B is the door and C an inner partition or front, which may also have a door to afford access to the instrument inside.

D designates the usual break-contact wheel, driven by an ordinary clock mechanism or train E, only shown diagrammatically in the drawings, as this is a common feature in the present art. On the same arbor a, Fig. 3, with a wheel b of the train is a disk F, which has in it a notch or recess c to be en-

gaged by a pin or stud d on a detent-lever G , so as to hold the driving mechanism against movement, and this lever is adapted to be lifted by an electromagnet H . These features in some form have been before used in this class of instruments.

The line-wires entering the box A are designated by W and W' . The current entering by W' under normal conditions when no signal is being sent goes to the binding-post of the brush e of the break-contact wheel D , thence by wire w to a contact f on the lever G , thence to a spring-contact g , thence through wires w' , w^2 , and w^3 to the button-closure, h (in Fig. 1,) and thence by wire w^4 to the line-wire W . This provides a short circuit which cuts or shunts out the electromagnet H and renders it inactive. Let us now suppose that the circuit is broken at the button-closure h . The current entering by the line W' then flows to the magnet by wires w , w' , and w^2 , through the coils of the magnet, and thence by a wire w^5 to the wire W . Thus the magnet is excited, and through means hereinafter explained lifts the lever G until the stud d is free from the recess c , and allows the driving mechanism to set the break-contact wheel D in motion; but the instant the lever G is lifted ever so little the circuit is broken at the contacts f and g , and the current must then flow through the brush e to wheel D , thence through brush e' to its binding-post, and thence by wires w^6 and w^2 to the magnet. The wheel D now becomes a circuit-breaker, and the current will be broken whenever the brushes pass off a tooth thereof.

The general features being now understood the means for breaking the shunt-circuit at h may be explained, premising that other devices the equivalents of that shown may be employed. A push-button I with a stem i appears in front of the partition C , and it is only necessary for the person wishing to send a signal to press or push in this button. The stem of the button, Fig. 3, plays in a tubular guide j on the back wall of the box, and when pressed in it compresses a spring k in this guide. Fixed on the stem of the button, Fig. 2, is a contact-piece m , which is held normally in contact with terminals n of the wires w^3 and w^4 of the shunt-circuit of the magnet by the spring k , thus providing the button-closure h . (Indicated diagrammatically in Fig. 1.) Also on the stem of the button is mounted a rocking cross-bar o , one arm o' of which is adapted to take under the detent-lever G when the button is pushed in and form an interposing piece. The other arm o of the cross-bar carries a pivoted latch-detent p , which when the button I is pushed in wipes under the detent-lever G and engages behind the latter, so as to prevent the return of the button by its spring k until the lever g is lifted high enough to free the upright arm

of the detent p . It may be stated here that any form of yielding detent can be employed for this purpose, that shown being a simple L-shaped gravity-detent pivoted to the cross-bar o at the angle formed by the two arms of the detent. 70

The armature q of the magnet H is carried by a lever J , which is fulcrumed or pivoted at r , and on the boss of the lever J is a pendent arm K , provided with a screw s , so disposed as to take under the piece o' when the button I is pressed in. The function of the arm K is to lift the detent-lever G , and the function of the screw s therein is to enable the impinging point of the lifting to be so varied in the different instruments in the system that each will begin to lift when the armature shall have reached a predetermined point in its movement toward the poles of the magnet. 80

It may be explained here that the stem of the button I plays slidably through a bearing in a bracket C' on the wall of the box and that there is a spline or feather i' on the stem, which engages a groove in the bracket to prevent the stem from rotating. The cross-bar o rocks on the stem; but the spline on the latter engages a recess in the bar and limits the extent of the rocking movement. When the button I is in its normal protruded position, the screw s , which is not directly under the lever G , may rise without lifting the latter; but when the button is pressed in it carries the bar o with it and moves the end o' of the latter under the lever G , so that when the screw s impinges on the interposed piece o' 90 the latter serves as an intermediary to lift the detent-lever. The end o' of the bar o being the heavier the bar assumes its normal position by gravity; but obviously its return to its normal position may be assured by any known means. 100

Fixed on the armature-lever is a curved rack t , which gears with a wheel u and rotates the same when the armature moves to and fro. Through intermediate gear-wheels v v' 110 the wheel u drives a ratcheted escapement-wheel x when the armature moves toward the poles of the magnet, thus providing a retarding device for the movement of the armature; but when the armature falls back the ratcheting of the escapement cuts it out and this backward movement is not retarded. 115

The operation of the device is as follows: If any one wishes to send in an alarm, he opens the door of the box and pushes in the button I . This sets the parts in position to operate, and the button is locked when pushed in. Now if this is the only box in the system from which a signal is being sent the pressing in of the button allows the current to flow 120 through the magnet and the signal will be automatically transmitted in due course; but should some other instrument—say 2—in the system be in operation sending a signal when the button I of an instrument—say 3—is 125

130

pressed, the instrument 3 will transmit its signal, but not until the instrument 2 shall have finished sending its signal. The reason for this is that the movement of the armature 5 of the magnet of instrument 3 is retarded so as to move slowly, and before it has an opportunity to lift the detent-lever G high enough to set free the driving mechanism the wheel D of instrument 2 will break the circuit and 10 allow the armature of instrument 3 to fall back. Thus while the instrument 2 is in operation the armature of the instrument 3 will oscillate—that is, move slowly toward the poles of the magnet and then fall back 15 quickly; but it will never move up near enough to the poles of the magnet to set the driving mechanism in operation or release the button I while instrument 2 is operating. As soon, however, as instrument 2 completes 20 its signal and the wheel D thereof stops, with the brushes e e' resting on a tooth, instrument 3 will proceed automatically and transmit its signal—that is to say, the armature q of its magnet will move up near enough to the poles 25 of the magnet H to cause the screw s in the arm K to impinge on the interposing piece o' of the cross-bar o, and through it lift the detent-lever G far enough to set free the disk F, thus setting the wheel D in motion. As the 30 lever G drops back at each break in the circuit at D the stud d falls on the edge of the disk F and rests there until the latter shall have made a complete rotation, when it will fall into the notch c and stop the driving 35 mechanism. The wheel D will be so geared as to stop with the brushes e e' resting on one of the teeth thereof, as seen in Fig. 1, so as to maintain the circuit unbroken at that point.

In order that the several transmitting 40 instruments may be so adjusted as to come into action successively in case two or more of them should be set for operation simultaneously, the screw s or some similar device is employed. The object is to adjust the instrument in such a manner that when the 45 electromagnets H are excited in all of them simultaneously the detent-lever G of No. 1 will start to rise first, then No. 2, and so on through them all. If the instruments are all 50 constructed alike, the screw s will be found a simple and convenient means for bringing about this successive operation; but many other ways of effecting the object will occur to those skilled in the art.

55 In the diagram, Fig. 4, Nos. 1, 2, and 3 designate several signal-transmitting instruments in the closed line-circuit and supplied by a battery or generator M, which may be at a central point or station L, where the receiving instrument is located. The instrument No. 1 is represented as sending a signal, the shunt about the magnet H being broken at h. The current entering at W' flows 60 through the coils of the magnet and thence 65 by a wire w² to the brush e, thence through

the break-contact wheel to the brush e', and thence out through line-wire W. The shunt about the break-contact device is broken in No. 1 at f by the lifting of the detent-lever G. In the case of the instruments No. 2 and No. 70 3 the shunts about the magnet H and the break-contact device are closed, and in these instruments the current enters at line-wire W', flows by way of wires w⁴, w³, w², and w⁶ to f, and thence by w to the outgoing line-wire 75 W. In Fig. 4 the disposal of the conducting-wires is slightly different from that shown in the principal views; but this is only for convenience in diagrammatic illustration. Obviously it is not important just how the wires 80 are strung in the instrument so long as the closed circuit is maintained and shunts are provided, as described.

It will be noted that this invention provides an instrument having in addition to its 85 non-interfering characteristics some manually-operative means, as the button I, for example, for putting the mechanism of the instrument in a potentially operative condition, whereby whenever the line becomes receptive, or is in condition to receive a signal from this instrument, such signal will be sent; but the manually-operative means does not in itself set the mechanism of the instrument 90 in operation. It merely puts it in such a 95 condition that it may and will operate whenever the line is receptive. This result is attained through the retardation of the mechanism, aided under some conditions by the regulation for successive operation. 100

Having thus described my invention, I claim—

1. An electric signaling instrument, having mechanism for transmitting a signal, means for setting said transmitting mechanism in 105 operation only when the line-circuit is receptive of the signal, an electromagnet which controls said means, a shunt about said electromagnet which cuts it out, normally, from the line-circuit, means for retarding the effective operations of said electromagnet until the line-circuit shall be receptive to the signal, manually-operable means for breaking 110 said shunt about the electromagnet when a signal is to be sent and putting the latter in 115 potentially operative condition, and means for holding said shunt open until the transmitting means has been set in motion.

2. An electric signaling instrument, having mechanism for transmitting a signal, an electromagnet, means controlled by the said electromagnet for setting said transmitting means in operation only when the line-circuit is receptive of the signal, automatic 120 means for retarding the operations of said electromagnet, means by which the said electromagnet is normally cut out from the line-circuit, manually-operable means for closing the circuit through the coils of said electromagnet, and means for holding said elec- 125 130

tromagnet in such potentially operative condition until the signal transmitting mechanism has been set in operation.

3. An electric signaling instrument, having a mechanism for transmitting a signal, means for setting said mechanism in operation only when the line-circuit is clear to receive the signal, an electromagnet which operatively controls said means, means by which said electromagnet is normally cut out from the line-circuit, manually-operable means for closing the circuit through the coils of said electromagnet when a signal is to be sent, means for holding said electromagnet in such a potentially operative condition until the signal-transmitting mechanism has been set in operation, and means for retarding the armature of said electromagnet.

4. An electric signaling instrument, having a mechanism for transmitting a signal, which includes a break-contact device, a shunt about said device which shunts it normally out of line-circuit, an electromagnet which controls said transmitting mechanism and said shunt and sets the said mechanism in motion only when the line is clear to receive the signal, a shunt about said electromagnet which normally shunts it out from the line-circuit, manually-operative means for breaking the shunt about said magnet when a signal is to be sent, means for maintaining the break in said shunt until the magnet shall have set the transmitting mechanism in operation and shall have broken thereby the shunt about the break-contact device, means for preventing the magnet from setting the transmitting mechanism in motion until the line is clear to receive the signal, and means for maintaining the break in the shunt about the break-contact device until the signal shall have been sent.

5. An electric signaling device, having a mechanically-operated circuit closer and breaker for signaling, mechanism for operating said circuit closer and breaker, a detent which arrests the operation of said mechanism, an electromagnet and its armature, means between said armature and said arresting-detent for setting the mechanism in operation when the electromagnet is excited, means for retarding the movements of the armature toward the poles of the magnet, a circuit for exciting the magnet, a shunt about the magnet which cuts it out normally, manually-operable means for breaking said shunt when a signal is to be sent, means for holding said shunt open until the driving mechanism is set in operation, a normally

closed shunt about the signal-transmitting circuit closer and breaker, and automatic means for breaking this shunt when the mechanism is set in operation.

6. An electric signaling device, having a break-contact wheel, brushes for said wheel in the line-circuit, mechanism for driving said wheel, detent means for arresting the movement of said driving mechanism, a shunt about said brushes which cuts them out, normally, from the line-circuit, means which breaks said shunt when the detent device is moved to free the driving mechanism, an electromagnet in the line-circuit, the armature of said magnet, means which retards the movement of the armature toward the poles of the magnet, means between the armature and the detent which arrests the driving mechanism, for operating said detent to release the driving mechanism, a shunt about the electromagnet which normally cuts it out from the line-circuit, a manually-operable button for breaking said shunt and allowing the current to flow through the magnet, and means for holding said shunt open until the driving mechanism shall have been set in motion.

7. An electric signaling device, having a mechanically-operated circuit closer and breaker for signaling, mechanism for operating this circuit closer and breaker, a detent which arrests the operation of said mechanism, an electromagnet and its armature, means for retarding the movement of said armature toward the poles of the magnet, a lever G carrying the said arresting-detent, an arm K, for lifting said lever to free the driving mechanism, said arm being actuated by the armature in its movements, a button I, a spring which presses said button outward yieldingly, an interposing piece carried by the button to connect the lever G and arm K operatively when the button is pushed in, a latch for locking the button when it is pressed in, said latch being freed by the lever G when the latter is lifted, a shunt about the electromagnet for cutting it out of the line-circuit, and a circuit-breaker actuated by the button I for breaking said shunt when the button is pressed in.

In witness whereof I have hereunto signed my name, this 12th day of October, 1904; in the presence of two subscribing witnesses.

PATRICK KENNEDY.
